UNITED STATES PATENT OFFICE.

MARTIN BOZSIK, OF HIBBING, MINNESOTA.

DESIGN FOR A CUSPIDOR.

41,787.

Specification for Design. Patented Sept. 19, 1911.

Application filed May 19, 1911. Serial No. 628,250. Term of patent 14 years.

To all whom it may concern:

Be it known that I, MARTIN BOZSIK, a subject of the King of Hungary, residing at Hibbing, in the county of St. Louis and State of Minnesota, have invented a certain new, original, and ornamental Design for a Cuspidor, of which the following is the specification, reference being had to the accompanying drawing, forming a part thereof.

The figure is a perspective view of the cuspidor, illustrating my new design.

I claim:—

The ornamental design for a cuspidor, as shown.

MARTIN BOZSIK.

Witnesses:

ROBERT STRATTON,
JOHN LOTZ.
